UNITED STATES PATENT OFFICE.

ELIHANAN L. MOODIE, OF NEW YORK, N. Y., ASSIGNOR OF ONE-HALF TO
CHARLES H. GILLESPIE, OF SAME PLACE.

DESIGN FOR AN ADVERTISING OR ORNAMENTAL BLANK OR EASEL.

SPECIFICATION forming part of Design No. 12,922, dated May 9, 1882.

Application filed February 27, 1882. Term of patent 3½ years.

To all whom it may concern:

Be it known that I, ELIHANAN L. MOODIE, a citizen of the United States, residing in the city and county of New York, in the State of New York, have invented and produced a new and original Design for Advertising or Ornamental Blanks or Easels, of which the following is a specification, reference being had to the accompanying drawing, forming a part thereof, the said drawing or pictorial representation being a front view illustrating my said design, a representation in cross-section being considered unnecessary, inasmuch as the blank or easel is to be supported by any of the means usually employed for like purposes.

The leading feature of my design consists in a novel configuration and graphic representation of the plate or face of an easel or equivalent blank for receiving or being impressed or marked with any suitable advertising matter, the said blank or easel being, moreover, capable of use for purely ornamental purposes when devoid of such advertising matter.

My said design comprises the representation of a cabbage, shown as having a parting or opening in the middle occupied by the representation of a human face, preferably one having the characteristic features, hair, &c.,

of a youth or child of the African race, the said representation of a human face thus surrounded by the representation of a cabbage producing a very unique, pleasing, and ornamental effect, calculated to attract attention both to its own characteristics and to any advertising matter that may be marked, printed, impressed, or otherwise provided upon it.

The representation of the human face aforesaid and of the cabbage may of course be colored or tinted with any appropriate color or tint to correspond to a greater or less degree with the natural color of said face and cabbage.

I do not claim a card having impressed thereon the pink, crimson, or purple representation of a rose with a miniature human face at the center thereof; but

What I claim as my invention is—

The design for an advertising or ornamental blank or easel herein shown and described, the same comprising essentially a representation of a cabbage having at its central portion the representation of a human face, substantially as described.

ELIHANAN L. MOODIE.
